ABSTRACT: The present invention consists of an electron beam apparatus for melting and/or evaporating metals in a vacuum such as in vapor coating processes or the like. The improvement of this invention is characterized in that the support for the metal to be evaporated forms a separation wall between an electron gun on one side and the material to be melted on the other, thereby electrically and magnetically shielding the melt metal. The support is preferably of thin foil to suppress heat conduction losses which may also be reduced in thicker support constructions by spoked support design.

APPARATUS FOR THE EVAPORATION OF MATERIALS IN A VACUUM

Apparatus for the evaporation of materials is known in which a so-called electron gun is arranged in a vacuum chamber. The electron gun beam, by its action in striking the material to be evaporated, heats it and brings parts of it to evaporation. The vapors so produced can be condensed to coat substrates arranged in the neighborhood with the mentioned materials, for example, glass plates, optical lenses and electron microscope specimens. A great advantage of the electron beam evaporation lies in the fact that an electron beam can be concentrated so that with sufficient focussing on a very small surface, a high energy density can be attained with a reasonable output and, thereby, a high temperature. Further, an electron beam can be easily deflected by electric or magnetic fields and, for example, can be directed alternately onto different materials which has significance for the production of mixed coatings. The energy carried over to the evaporation material is conveniently and accurately controllable with electron beam heating, which is important for the automation of evaporation equipment. Surprisingly, it has been shown that it is also possible to evaporate nonmetals with the electron beam, for example, quartz. The electron beam would represent the ideal means for the vacuum evaporation of material of this kind were it not also associated with some serious disadvantages.

One disadvantage arises from the unavoidable ionization of vapors by the beam. This can have, as a consequence, an asymmetric charging of the substrate, which often leads to condensation with undesirable distribution or structure. In order to overcome this disadvantage, as has already been proposed, a metallic gauze or grid is arranged as a screening electrode between the vapor source and the surface to be evaporated on for the purpose of intercepting the annoying charge carriers, electrons or ions. Unfortunately, it becomes evident that a device of this kind, placed in the path of the vapor, brings with it as a disadvantage the danger of shadowing parts of the condensation surface. Also, if the mesh of the gauze or the spaces between the wires of the grid are too large, it becomes too inefficient. On the other hand, if the spaces between the gauze or grid are too small, they can grow together as the result of condensation.

Another disadvantage of the electron beam arises from the fact that it is unavoidably associated with electric and magnetic fields. First of all, these fields can quite generally impair any electrical measurements in the evaporation equipment. They are especially disturbing if one wishes to undertake condensation on the substrate in quite definitely oriented electric or magnetic fields, as for example, in the production of magnetic thin films with prescribed preferential direction of magnetization (for storage elements of computers) or in the production of optically polarized layers by the evaporation of dielectrics in directed electric fields. The mentioned fields are also disturbing when electron-optical experiments should be carried out on an evaporated layer in the formative state.

The present invention has set as its object an apparatus with the practical advantages of electron beam evaporation without limiting its utilization by the aforementioned disturbing disadvantages. The apparatus according to the invention relates to the evaporation of materials in a vacuum through electron bombardment and is characterized in that the support serving for the evaporation carrying the evaporation material is formed as a part of the separating wall electrically shielding two regions of space from one another. The apparatus for heating the separation wall by electron bombardment is provided in the one region of space, while the side turned away from this apparatus is formed for the reception of the material to be evaporated.

The use of the invention has the advantage as compared with the direct bombardment of the evaporating surface of the material that essentially the heat transfer must only be effective on the material to be evaporated and the heat leakage through the support can be kept very small in contrast to all other known heating processes. In the known method of re-

sistance heating, for example, with a tungsten strip serving as a material support, the heat produced by the current flowing through it is uniformly distributed over the whole surface of the heating ribbon. Only a small part of this surface, which stands in direct contact with the material to be evaporated, is useable as a true support for the transfer of heat. At least 80 percent of the heat energy produced goes off by free radiation and is lost by the conduction of heat to the two connecting electrodes. In contrast, with electron beam heating, one may limit the production of heat to that place on the support where it is immediately transferred to the material to be evaporated. Since the part of the support not covered need not be subjected to the electron bombardment, the radiation loss can be held substantially smaller.

BRIEF DESCRIPTION OF THE DRAWING

FIG. 1 shows an embodiment of my invention wherein the evaporation support may be formed of an electrical conductor such as metal, carbon, graphite, or the like.

FIG. 2 shows an embodiment of my invention utilizing a cooled, double-walled return-current shell in which the evaporation support may be a nonconductor of electricity.

FIG. 3. shows an evaporation shield for use with my invention.

FIG. 4 shows the embodiment of FIG. 1 to which has been added means for providing change of the evaporation shield and material.

A first example of the application of the invention is illustrated in the accompanying FIG. 1. The apparatus is built up on the flange 1 which can be secured in an opening in the baseplate of a vacuum evaporation equipment. The numeral 2 designates an annular-shaped sealing groove with an elastic sealing ring (O-ring gasket) 3, 4, a cylindrical, electrically-insulating part, for example, of porcelain, 5 a cylindrical metal shell surrounding the part 4, and 6 a hot cathode which is supplied with heating current through the vacuum tight, electrically-insulated feedthroughs 7 and 8 from the source 9 and with a negative accelerating potential for the electrons of a few one hundred to a few one thousand volts. On the metal shell 5, which stands in electrically-conducting connection with the flange 1, there lies a thin metal disk 10 of a refractory material (metal) which serves as an evaporation support for the material to be evaporated and is provided in an advantageous way with a depression 11 for the receipt of the same.

In operation, the electrons emitted from the cathode 6 are accelerated onto the evaporation support 10 and heat it according to the energy transferred. The inner wall of the electrically-insulating part 4 receives a negative surface charge through scattered electrons, which concentrates the beam current to the extent that it only strikes the part of the thin sheet 10 which serves for the evaporation. Obviously, more complicated known electron optical electrode arrangements can also be used in order to produce a sharply-focussed electron beam on the place of evaporation.

The thinner the thin plate 10 is chosen, which serves as the evaporation support, the better one can preserve the known advantages of the conventional kind of electron beam heating without having to count the cost of its disadvantages.

Any known electrically-conducting refractory material can be used as the high temperature stable material for the part of the electrically-shielding separation wall serving for the evaporation which exhibits a sufficient mechanical strength. Those known materials to be considered first are those usually used for evaporation with resistance heating, such as tungsten or molybdenum sheet or else foils. Also, nonmetals, for example, plates of carbon, graphite and carbides etc. may be used. Nonconductors of electricity can also be used, for example, plates of oxides if an electron gun with a focussed beam is used for the electron bombardment, such as, for example, provided in the arrangement shown in FIG. 2 as will be later described. 75 The auxiliary electrode 26 can be eliminated and the return

current flow from the point of bombardment by the electrons on the insulating support 25 results from the scattering or thermal emission of electrons which are collected by the neighboring parts of the inner walls of the shielding 20.

The metal shell 5, together with the thin sheet 10 form an electrically-shielding separation wall between a region of space "A", containing the cathode 6 and the space region "B" in which the evaporation takes place.

The regions of space "A" and "B" are not only electrically shielded one from the other, but also largely magnetically shielded. The return flow of the electron beam current going out of the cathode 6 is uniformly distributed radially over the disc 10 and along the shell 5. The magnetic effect of the electron current and the return current largely cancel each other in this way. In order to eliminate the magnetic effect of the cathode coil 6, it must be built free of induction, for example, it is built up as a double winding as is well known.

In order to almost completely eliminate the magnetic effect of the beam current and the cathode heating current, one can, within the scope of the invention, also make use of the known magnetic shielding materials. An additional shield of such material may be provided that substantially surrounds the space "A" where only an opening for the exit of the vapor stream produced must be left free. One can also manufacture the flange 1 and the shell 4 of FIG. 1 themselves out of magnetically shielding materials so long as the return current is not too great, considering the poorer electrical conductivity of these materials.

Another form of application of the invention is shown in FIG. 2. It is differentiated from FIG. 1 by a differently-formed double-walled return current shield 20 into whose annular hollow space a cooling medium is led, through the conduit 22 and out again through another conduit 23. The electrode 26, held at the same or higher negative potential than the electron emitting hot cathode, is provided in order to concentrate the electrons escaping from the cathode 24 onto the evaporation support 25. The gap between the electrode 26 and the neighboring wall of the return current shell 20 is made so small that no electrical gas discharge can appear. It is well known that this will be the result if the theoretical mean free path length of the electrons in the gas situated in the gap is substantially greater than the gap width (gap widths of 1 mm. are suitable in most cases). The electrode 26, for example, of copper, can be so formed that it acts as a concave mirror for the heat radiation emitted from the cathode. Thus, heat is focussed back onto the cathode which produces a better utilization of the energy.

The two previously-described examples have the advantage that those parts of the separation wall serving for the electrical shielding and which serve for the evaporation are very easily replaced and without great expense. Since the sheet serving as the evaporation support is thin and its forming cost is low, in contrast to the production of boats for evaporation, which must be made of the same refractory metals, such as tungsten

or molybdenum, one works very economically according to the invention on these grounds.

The evaporation support itself can exhibit different forms, for example, for the purpose of the least possible heat conduction, it can be formed of tightly woven wire mesh where the melt of the material to be evaporated is held together by its surface tension.

FIG. 3 shows, in an enlarged sketch, a form of the application in which only the central part 31, carried by the narrow 10 spokes 30 serves as the evaporation surface and it likewise has the advantage that the conduction of heat from the evaporation surface is solely through the spokes and is very small, particularly since the return current flows through them and thereby warms them. For that reason, one may also use a 15 thicker sheet which results in a longer useful life. It is evident that the small cutout portions 32 will markedly influence the electrical shielding of the separation wall.

In many applications, the longest possible useful life of the evaporation support plays a decisive role (although they are 20 cheap and easy to replace) namely when a greater amount of material should be evaporated without the necessity of breaking the vacuum. In these cases, one can use an arrangement as is shown in FIG. 4. This example shows a relatively similar construction of the electron beam producing apparatus as that 25 in FIG. 1; however, the evaporation support is formed as an annular channel 40 in a rotating disc 41. Through this, one gains not only a greater heating surface which can receive more evaporation material 42 at one time, but one can, for example, provide an addition mechanism 44 to the annular 30 channel which is indicated as a funnel in FIG. 4.

It should be mentioned further that the invention is especially suitable for the recently used multiple flash evaporation technique for the evaporation of mixtures in which the intermittent use of very high electron beam currents is necessary. 35 The electric and magnetic fields occurring in this case disturb not only on account of their absolute magnitude, but also because of their time variation through which undesired changing potentials are produced in electrical conductors which can be very disturbing to measurements.

I claim:

1. An apparatus for evaporating in a vacuum a material disposed upon a support, comprising:
means for generating an electron beam; and
an electrically conducting housing having integral outer and inner walls, said inner wall spaced from and surrounding said electron beam generating means so that no electrical gas discharge can appear therebetween, said inner wall is further formed to position said material support so that the material located therein may be vaporized.

2. An apparatus as recited in claim 1 wherein said inner and outer walls form a chamber having means for receiving and discharging a coolant so that when said material is vaporized by said electron beam generating means said housing may be cooled.
